United States Patent Office.

SAMUEL RICHARDS, OF PHILADELPHIA, PENNSYLVANIA.

Letters Patent No. 71,642, dated December 3, 1867.

IMPROVED SNOW-PLoughS.

The Schedule referred to in these Letters Patent and making part of the same.

TO ALL WHOM IT MAY CONCERN:

Be it known that I, SAMUEL RICHARDS, of the city of Philadelphia, State of Pennsylvania, have invented a new and useful Improvement in Constructing Snow-Ploughs; and I do hereby declare the following to be a full and exact description of the same, reference being had to the annexed drawings, making a part of this specification, in which—

Figure 1 is a front removable triangular piece, bolted to the front of the car-frame.

Figure 2 is another triangular piece to be mounted upon and bolted to the front of the car-frame.

Figure 3 is a movable wedge-piece to be attached by a pivot-bolt near its upper end.

Figure 4 is one of a pair of removable side pieces, screwed to each side of the car-frame.

Figure 5 is an ordinary eight-wheel flat car, used on railroads for carrying.

Figure 6 is a view of my plough, with all the parts in place, firmly attached to the car.

The nature of my improvement consists in the mode of constructing a snow-plough, which can be rapidly and cheaply put together, and which can be taken apart and the car-bottom used, and the other parts stored in small compass.

I take an ordinary eight-wheel flat car or car-bottom, such as used upon most roads. I construct a piece, of the form shown in fig. 1, of two-inch timber, so that the back edge, A, of its inclined surface fits evenly with the front edge, B, fig. 5, of the car-bottom, and fastened to the car-frame by a long steel rod or bolt, m, which passes through its side at C, then through perforated bolt-heads D D' D'', fig. 5, and the supports C' C'' alternately, and after passing through the side C'' is secured in place by a screw-nut, thus holding the triangular piece firmly in position. I then construct another piece, of the form shown in fig. 2, of the same thickness of timber, so that when in place its front edge meets the back edge, A, of piece shown in fig. 1, the upper surfaces of the pieces thus forming one continuous inclined plane. The inclined surface of this piece contains a slot, E, fig. 6, in which works a projection from the bottom of the wedge-piece, shown in fig. 3, and is secured in its place by bolts dropped through holes in its bottom into corresponding holes bored into the car-floor or bottom. On top of this piece is placed a wedge-piece, as shown in fig. 3, which is pivoted at its back extremity to the upper plane surface of fig. 2. To the front of this wedge is secured a flap, G', which projects, when all the parts are in place, a little way over the lower section or piece F of the inclined plane, fig. 6. When the side pieces, one of which is shown in fig. 4, are in place, as at H, fig. 6, my plough is complete. The wedge-piece G has a projection on its under side, fitting in the slot E, fig. 6, in the inclined plane F'. This projection is moved from side to side by means of two pulley-blocks attached to the under side of inclined plane F, at each end of the slot E. A rope or chain, attached by one end to this projection is passed through one of these pulleys, and after several turns around a roller or windlass, I, fig. 2, is taken through the other pulley, and its loose end also attached to the projection, thus making an endless cord.

I prefer to have this wedge-block so as to shift, in the manner described, from side to side, and so as to be removable also, but it may be fixed to the plane rigidly, so as neither to vibrate nor be removable. In the manner in which I have described it it may be adjusted, so as to throw the snow off on these or both sides of the plough. The flap G' is adjustable by means of the lever K, which can be secured in place by the pin L. The side pieces H serve not only to prevent the snow as it is thrown aside from falling under the wheels, but act also as braces or supports to the front section or piece F of the plough.

Having thus described my invention, what I claim, and desire to secure by Letters Patent, is—

1. Combining, with an ordinary eight-wheel flat car or car-bottom, the removable front plane F and the removable inclined top piece F'.
2. Combining, with an ordinary eight-wheel flat car or car-bottom, the removable front plane F, the removable inclined top plane F', and the upper wedge-block G, or their equivalents.
3. The arrangement of an axle or windlass, I, endless cord, and shifting wedge-piece G, or their equivalents.

SAMUEL RICHARDS.
